UNITED STATES PATENT OFFICE

109,324

DESIGN FOR LEATHER OR SIMILAR ARTICLE

Herman Kass, New York, N. Y.

Application February 8, 1938, Serial No. 74,964

Term of patent 3½ years

To all whom it may concern:

Be it known that I, Herman Kass, a citizen of the United States, residing in New York city, in the county of New York and State of New York, have invented a new, original, and ornamental Design for Leather or Similar Article, of which the following is a specification, reference being had to the accompanying drawing forming part thereof.

The figure is a plan view of the leather or similar article embodying my new design.

I claim:

The ornamental design for leather or similar article, as shown and described.

HERMAN KASS.
